SCISSORS JOINT AND BLADE TENSION
MEANSDonivan C. Feather, Portland, Oreg., assignor of
one-third to James B. Pfouts, Portland, Oreg.

Application January 29, 1945, Serial No. 575,046

6 Claims. (Cl. 30—269)

1

This invention relates to scissors, shears and so forth. The primary object of the invention is to provide an automatic blade tensioning or adjustment device embodied in the pivot bolt of the shears.

A further object of the invention is to provide a tensioning device that will press the blades together with a minimum of pressure depending upon the toughness of the material being cut, as for instance in the cutting of thin light material it is not desirable to have a heavy pressure between the blades, but on the cutting of thick tough material it is desirable to be able to apply a greater leverage or tension in bringing the blades together. With my invention this is automatically accomplished, which will be more fully described and illustrated later in the specification.

These and other incidental objects will be apparent in the drawings, specifications and claims.

Referring to the drawings:

Figure 1 is a conventional type of scissors having my new and improved tensioning device embodied therein.

Figure 2 is a cross section of the scissors, taken on line 2—2 of Figure 1, looking in the direction indicated.

Figure 3 is the same as Figure 2, except where a greater leverage is being applied in bringing together the blades.

Figure 4 is another preferred form of tensioning device.

Figure 5 is an additional feature added to that shown in Figure 4.

In the drawings:

The conventional scissor is indicated at 1, having the customary blades 2 and 3 pivotally connected together by the bolt 4. The bolt 4 in this instance embodies my invention, which consists of having a shoulder 5 and a head 6 formed thereon at one of its ends. The bolt passes through the hole 8 of the blade 2, which is slightly larger than the bolt, the reason for which will be more fully described later. An enlarged hole 7 is formed within the blade 3 and receives the shoulder 5 therein, having a clearance 9 surrounding the shoulder 5. The bolt and the blades are held in an assembled position by burr 10, or it may have a nut threaded thereon against the removable cap or retainer 11, which is fitted to the outer end of the bolt 4. Within the cap 11 is a lock washer 12, which supplies an initial pressure between the head 6 of the bolt and the cap 11 against the blades 2 and 3, maintaining the proper tension

2

between the blades for cutting thin or ordinary material.

Referring to Figure 3, I illustrate my device where a thick heavy material is being cut, as pressure is applied to the scissor handles the blades 2 and 3 offset one past another as illustrated by the arrows, compressing the washer 12 and creating a leverage between the head of the bolt 6 and the washer as illustrated in the drawings, the shoulder 5 contacting the periphery of the hole 7 of the blade 3 at 13 exerting pressure diagonally opposite this point between the washer 12 and the side of the blade 2 at 14. The greater the pressure required to the offset movement of the blades 15 depending upon the toughness of the material to be cut, will determine the pressure exerted at points 13 and 14, bringing the blades together to offset the spreading action of the cut. The pressure at points 13 and 14 is obtained by the clearances 8 and 9 permitting the bolt 4 to assume the angle or position shown in Figure 3, when the blades are offset in the cutting action. From the above description it can be readily understood that I have provided a suitable blade tension 20 within the washer 12 for ordinary cutting, saving wear and tear on the shears and fatigue to the operator, but when extra heavy work is to be performed I have provided a means of applying the extra tension for maintaining the blades in proper working relation with each other by allowing the bolt 4 to bring the blades tightly together as illustrated.

Referring to Figure 4, I have illustrated a modified form of construction, wherein the pivot bolt 15 is slidably mounted within the scissor blades 16 and 17. This bolt fits snugly within the hole of the blade 16, but is movable longitudinally therein, the blade 17 being formed with a relatively enlarged hole 20 through which the bolt passes. A sleeve 18, having one of its ends 19 contacting the surface of the blade 16, at the inner end of the hole 20 of the blade 17, and its opposite end having a flange 21 contacting the inner rim 22 of the head of the bolt 15 maintaining the blades and sleeve in alignment. When pressure is applied to the handles of the shears, the blade 17 will tend to offset, tilting the sleeve as illustrated, causing the end 19 of the sleeve 18 to contact the wall of the hole 20 at one point, as shown in Fig. 4, and compel a tilting movement of the sleeve 18 in the hole 20. This tilting movement of the sleeve 18 forces the flange 21 to engage the outer surface of the blade 17 at 23 and the inner face of the head of the bolt 15 at 24, providing a leverage between the points 24 and

23, forcing the blades together, first against the spring washer 30, compressing the same for light cutting, then applying the leverage between the points 24 and 23 for heavy cutting as heretofore described in Figures 2 and 3.

Figure 5 illustrates a modification of Figure 4, wherein the spring washer 25 maintains a slight initial pressure within the head of the bolt 15, the bolt 15 being threaded into the blade 16 instead of having a sliding fit.

I do not wish to be limited to the exact structure as illustrated, as other mechanical modifications may be employed still carrying out the spirit of my invention.

What is claimed as new is:

1. Means for automatically increasing the tension on the blades of scissors or the like, including a pivot uniting the blades, the blades being formed with pivot receiving openings of a size to permit relative tilting of the pivot, an independent tensioning element responsive to such pivot tilting, and means for tilting the pivot and tensioning the element to increase the pressure on the blades under increasing resistance in the operation of the blades.

2. Means for automatically increasing the tension on the blades of scissors or the like in accordance with the resistance of the blades in use, comprising a pivot for connecting the blades, the blades being formed with pivot receiving openings at least one of which is of a size to permit relative tilting of the pivot, means for tilting the pivot under pressure on the blades, and a spring washer on the pivot to be compressed under the tilting of the pivot to increase the pressure on the blades.

3. Means for automatically increasing the tension on the blades of a scissors or the like in accordance with the resistance of the blades in use, comprising a pivot for connecting the blades, the blades having openings for receiving the pivot at least one such opening being of greater diameter than that of the pivot, an element forming part of the pivot and cooperating with the rela-

tively enlarged opening under excess strain to tilt the pivot, said element under tilting acting to exert pressure on one blade toward the other, and a spring washer on the pivot to be placed under increased tension relative to normal in the tilting of the pivot.

5. A means for automatically increasing the tension on the blades of a scissors or the like in accordance with the resistance of the blades in use, comprising a pivot for uniting the blades of the scissors, the blades being formed with pivot-receiving openings, the opening in one blade being enlarged and the pivot having a head beyond one blade, a spring washer encircling the pivot beyond the other blade, and an element on the pivot and located in the enlarged pivot opening and having a part to cooperate with the wall of the enlarged blade opening to tilt the element under excess strain on the blades and a part to bear on the outer surface of a blade to force such blade in a direction to compress the spring washer under greater than normal strain on the blades.

10. A construction as defined in claim 2, wherein the pivot includes a pin and a sleeve encircling said pin and movable by one blade under pressure on the blades in use to increase the tension of the tensioning element.

15. A construction as defined in claim 2, wherein the pivot is provided with a flanged element to overlie one blade, and said spring washer is seated within said element.

20. A construction as defined in claim 2, wherein the pivot is provided with a flanged element to overlie one blade, and said spring washer is seated within said element.

25. DONIVAN C. FEATHER.
